APPARATUS FOR AND METHOD OF MAKING
PRINTING SCREENS

Albert C. Cluzel, Ridgewood, N. J.

Application August 25, 1949, Serial No. 112,331

10 Claims. (Cl. 29—148)

1

This invention relates to a machine for and a method of affixing web material such as cloth in tightly stretched condition over a surface of an article such as a frame, as in the making of silk printing screens.

The machine and method of the invention are useful wherever a somewhat extensible web material of considerable strength must be stretched over an article such as a frame; in such applications the invention permits the attainment of tensions in the web material which are substantially equal in all directions. The machine and method of the invention are perhaps best illustrated in connection with the stretching of silk or the like cloth web over a frame in the making of printing screens.

The screen stencil ordinarily used in screen stencil printing consists of bolting silk stretched over a wooden frame. On this silk the design to be printed is applied either by stencilling or by photographic means, in the latter method, the silk being impregnated with light sensitive material on which the pattern to be reproduced is projected, the resulting picture on the screen then being developed. The stencil thus produced is further treated by painting the area which is to remain white with some substance such as gum or shellac which will make the silk impervious to the ink used. The stencil is placed in contact with the surface to be decorated and a puddle of ink is scraped from one end to the other by means of a rubber squeegee. This forces the ink, which resembles ordinary house paint, through the open areas of the stencil and it adheres to the surface beneath. The stencil is then lifted from the decorated surface and the ink allowed to dry, after which another color may be applied from another stencil, and so on.

It can readily be seen from the above that in order to produce first-class printed work it is necessary that the silk forming the screen be stretched tightly and substantially uniformly as to tension in all directions. Unless these conditions are present the screen will become distorted during use and it will be impossible to secure registration as to the different colors printed on the same article from successive stencils. In the prior art, the silk stencil screens have been formed by stretching the silk manually over the frame, fastening it to the frame as the stretching proceeds locally. It will be appreciated that by such method it was impossible to secure screens in which the warp and weft threads remained at right angles to each other substantially throughout the area of the

2

screen and in which the silk was subjected to substantially equal tension in all directions.

It is accordingly, among the objects of the present invention to provide a rugged, easily operated, machine for the stretching of flexible web material over the surface of an article such as a frame.

A further object of the invention resides in the provision of a machine in which the front corners of the web to be applied to the article are pulled away from each other to put the front edge of the web initially under tension which is equal to that subsequently applied transversely of the web in other portions thereof.

Yet another object of the invention resides in the provision of a machine in which the front and side edges of the web adjacent the article such as a frame to which it is to be attached are clamped and stretched to substantially equal amounts.

A further object of the invention resides in the provision of apparatus of the class described in which the web, while thus clamped on its forward and side edges, and while pulled back-wardly, is subjected to substantially equal and uniform tensions throughout its extent over and in contact with the frame, whereby the web may be applied in such condition to the frame.

A further object of the invention resides in the provision of an improved method of conditioning the flexible web material and of stretching it as a preliminary step to its affixation to a frame.

The above and further objects of the invention will become more readily apparent in the following description of preferred embodiments of the apparatus and method of the invention.

In the drawings accompanying the specification and forming a part thereof:

Fig. 1 is a view in plan of a preferred apparatus in accordance with the invention, the spindle for supporting the roll of web material being empty;

Fig. 2 is a view in vertical cross section through the apparatus of Fig. 1, the view being taken along the line 2—2, in Fig. 1;

Fig. 3 is a view in vertical section through a front corner engaging clamp of the machine, the section being taken along the line 3—3 in Fig. 1;

Fig. 4 is a fragmentary view in side elevation of the apparatus of Figs. 1 and 2, the view being taken from a point of view along the line 4—4 in Fig. 1;

Fig. 5 is a fragmentary view in perspective, partially in vertical section, of the apparatus in the vicinity of a movable front corner engaging clamp;

3

Fig. 6 is a view in perspective of a finished, covered frame, the silk screen being omitted from a part of such frame; and

Fig. 7 is a view in vertical cross section through the machine shown in Figs. 1, 2, etc., the section being taken along the line 7—7 in Fig. 1;

In the preferred embodiment of the apparatus shown, there is provided a main frame composed of a first, vertical frame member designated 2, a second vertical frame member designated 4, members 2 and 4 being positioned at the front of the machine, and two parallel vertical frame members 6 and 8 positioned at the rear of the machine. Vertical frame members 2 and 6 are connected together by the bottom tie member 10 which rests upon the floor or other support, and vertical frame members 4 and 8 are similarly connected together by the bottom tie member 12. Frame members 2 and 6 are further connected together by the top horizontal tie member 14, and vertical frame members 4 and 8 are similarly connected by the horizontal top tie member 16. Frame members 2 and 4 are further connected by the horizontal intermediate angle member 18, there being a corresponding angle member 20 intermediate the top and bottom ends of the rear frame members 6 and 8. Members 18 and 20 form the support for the platform raising jacks, subsequently to be described. The main frame of the device is completed by the top cross tie member in the form of an angle iron 22 connecting vertical frame members 2 and 4, a similar connecting angle member 24 connecting the rear vertical frame members 6 and 8.

A rearwardly extending sub-frame, at the right in Figs. 1 and 2, is provided by the horizontally extending upper members of which one is shown at 26 in Fig. 2, member 26 being supported at its outer end by means of the vertical frame support 28. A similar vertical support 29 is provided for the horizontal member 32 corresponding to member 26 at the other side of the frame, the side frame members being tied together at their bottoms by the angle iron 30.

The above described rear sub-frame forms the support for the supply of silk in the form of the roll 34 which is supported upon the spindle 36. Spindle 36 in turn is carried by the bearing 38 supported on frame member 26 and in the bearing member 40 located on horizontal frame member 32. A crank handle 42 is provided supported on one end of spindle 36, as shown in Figs. 1 and 4, there being provided on the spindle adjacent the crank the ratchet wheel 44 which coacts with pawl 46 mounted on frame member 32 in such manner as to hold the roll 34 in web tightening condition when the pawl is placed in operative relation with respect to the ratchet wheel, as shown more clearly in Fig. 4.

The silk web issuing from roll 34 is designated by the reference character 48. When such web reaches a position in which it lies over the wooden frame to which it is to be attached, and also when it is in attached condition on the frame, it is designated 48'. The web 48 progresses from roll 34 first upwardly over an idler roll 50. Roll 50 is supported at its ends in yokes provided in parallel, spaced, rearwardly directed supporting arms, one of which is positioned at each side of the machine. In Fig. 4 one such arm 52 and the yoke 54 supporting roll 50 are shown. After running over roll 50, web 48 progresses downwardly beneath the floatingly mounted vertically guided idler roll 58 disposed in the tank 56. Tank 56 is in the form of a trough positioned between

4

and supported by the above mentioned side supporting arms of which one is shown at 52. The vertical sides of the inner surfaces of the parallel supporting arms, which form the ends of the tank, are channeled vertically as shown at 60 on arm 52 (Fig. 4). Such vertical channels in the side arms allow the roll 58 to slide freely and to be guided vertically within such channels. Roll 58 depresses web 48 well beneath the surface of the liquid 57 carried in the preliminary conditioning tank 56. Ordinarily liquid 57 will be water. Web 48 rises from beneath the weighting roll 58 out of the liquid in the tank and into the nip between the bottom and top squeeze rollers 64 and 66, respectively, which are mounted in the vertical squeeze roller housing 62. Adjustable screw down members, such as 68, are provided in the housing to vary the compression to which the web is subjected. Rolls 64 and 66 have the function of removing excess moisture from the web and of flattening it as a preliminary to its being stretched over the wooden frame.

From the squeeze rollers web 48 is led beneath the idler roll 74 which is placed at such level as to insure that the end of the web rearwardly of the wooden frame to which it is to be attached lies below the top surface of such frame when the latter is in elevated position, and substantially at the effective clamping level of the front and side clamps, to be described. In initially threading the machine, web 48 is led from roll 34 and is introduced manually over roll 50 and thence between the squeeze rollers 64 and 66. The shaft 70 of the top squeeze roller is provided at one end with an operating hand wheel 72, whereby the squeeze rollers may be operated to feed the web therethrough. After the web has been fed between the squeeze rollers, the weighting roller 58 may be introduced into the slots in the trough supporting side arms, thereby to depress the web into the liquid in the tank. Supported on the horizontal intermediate cross tie members 18 and 20 are the two parallel inverted channel members 76 and 78, as indicated in Figs. 1, 2 and 7. On channel member 76 (Fig. 2) there is shown supported a portion of the mechanism for raising or lowering the frame supporting platform of the machine. Four platform raising jacks are provided, the two jacks or screws at the front being designated 82 and 83, and the two screws at the rear being designated 84 and 85. Each of the screws 82 and 84 (Fig. 2) is supported on a block 80 which lies on cross member 76. The screws extend freely through openings in blocks 80, screw 82 being threadedly engaged with and supported by the bevel gear 86 which rests in a bearing on block 80, and screw 84 is threadedly engaged with and supported by the similar bevel gear 88. Gears 86 and 88 are connected together by means of the horizontal shaft 90, each end of which carries a bevel gear meshing with the corresponding gear 86 and 88. Jack screws 83 and 85 are similarly connected and similarly supported, the screws being connected by the horizontal shaft 98, as indicated in Figs. 1 and 7. Shafts 90 and 98 are geared together for simultaneous and equal motion, whereby the jack screws 82, 83, 84 and 85 are all moved in the same direction and in equal amounts.

The means for connecting and driving shafts 90 and 98 takes the form of a horizontal transverse shaft 96, on one end of which there is connected a gear 94 which meshes with the gear 92, as shown in Fig. 2. A corresponding gear set, generally designated 100 serves to connect the

throughout the length of the frame 114, and with the tension from beneath the web by the elevating platform, that when applied to the frame the silk will have a substantially uniform tension in all directions. After the web has been subjected to the back tension, as described, its side edges are then clamping engaged by means of the side clamps 188 and 190, the prongs carried by the lower portion of the clamp, as in the case of the central clamps 120 and the corner clamps 148 and 150, penetrating the web material and the upper movable clamping member holding it tightly into engagement with the bottom clamping plate. Thereupon crank 228 is turned to move clamps 188 and 190 apart to subject the web throughout the length of the zone overlying frame 114 to substantial transverse tension. Usually clamps 188 and 190 are moved apart a distance substantially equal to that which clamps 148 and 150 were moved apart.

With the cloth thus held and stretched on its forward end, being given a predetermined back tension by means of the ratchet device on the supply spindle, being engaged along the side edges thereof and being given a transverse tension by the side clamps 188 and 190, the handle 102 is then turned to raise screws 82 to 85, inclusive, thereby to bring the platform 104 and the frame 114 into engagement with the under side of the portion 48' of the web. The raising of the platform is continued until the upper surfaces of frame 114 lie somewhat above the bottom surface of the pressing roll 74, the effective level at which the web is clamped on its side portions by clamps 188 and 190, and the effective line along which it is clamped by the front edge engaging clamps 120, 148, 150, 184 and 186. The amount of tension thereby additionally imparted to the web 48' by reason of upward movement of frame 114 may be correlated with the initial tension transverse to the forward edge thereof, the rearwardly directed tension imposed by the ratchet and pawl on the supply spindle, and the transverse tension applied by the side clamps. It is possible, by thus correlating the various tensions imparted to the web, to subject the portion thereof lying above the frame 114 to tensions which are substantially uniform in all directions therealong.

With the web 48' thus stretched over the frame 114, it is secured to the frame by means such as tacks or, in the embodiment shown, the staples 236 which are applied conveniently by means of a hand held stapling machine. After the web 48' has thus been firmly secured to the frame, the platform 104 of the machine is depressed to relieve the bottom of frame 114 from the platform, after which the back tension on the web is released by release of the pawl 46. The web material 48' is then cut transversely rearwardly of the frame, after which the forward and side edges of the web are released from the forward and side edge engaging clamps of the machine. The covered frame may then be removed from the machine and the projecting edges of the web trimmed therefrom.

In some instances it will be sufficient to rely only on the tension initially applied to the forward edge of the web, the back tension and the transverse tension throughout the length of the zone overlying the frame to which the web is to be attached, to secure the desired tensions in various directions in the web attached to the frame. In such cases it is necessary only to elevate platform 104 sufficiently to bring the upper surface of frame 114 into contact with the

underside of the web. It is usually preferred, however, to add to such tensions as that resulting from elevation of platform 104 to a point such as shown in Fig. 7. Such procedure is especially advantageous when the frame 114 is of the type in which the upper web engaging surfaces are curved, an inner longitudinal zone of the upper surface of each frame member being higher than the outer edge thereof. With such frame, which, like frame 114, above described may be made of materials such as metal as well as of wood, the application of the web fastening means to the frame at zones outwardly of said inner, high, longitudinal zones is facilitated when the web is pulled downwardly on all sides below the top of the frame.

Whereas for purposes of illustration I have shown and described a preferred embodiment of the apparatus for making printing screens of the invention, and also a preferred embodiment of the method of making printing screens, it is to be understood that such apparatus and method are illustrative only and that the invention is capable of considerable variation as to details of construction of the apparatus and application of the method. The invention is, therefore, defined by the scope of the claims appended hereto.

I claim as new the following:

1. Apparatus for stretching a web of flexible, somewhat extensible, material preliminary to its attachment across the face of an article, comprising means for holding said article to be covered, means for positioning a web of such material, of sufficient length and width to cover the face of the article, substantially in a plane parallel to and spaced from the said face of the article, said last named means comprising means for gripping the opposite corners of one end of the web, means to move such corner gripping means apart to subject such end of the web to tension in a direction transverse to the length of the web, means for gripping the central portion of such end of the web, means for applying a tension to the web longitudinally thereof over substantially its entire width, means to grip the side edges of the web throughout the length of the article, and means to advance the article holding means and the stretched web relatively toward each other to contact the surface of the web with the surface of the article to be covered and to subject the web additionally to tension.

2. Apparatus for stretching a web of flexible, somewhat extensible, material preliminary to its attachment across the face of an article comprising means for holding said article to be covered, means for holding a roll of web material, means for feeding web material from the roll, means for positioning a portion of the forward end of the thus fed web material of sufficient length and width to cover the face of the article, substantially in a plane spaced from the said face of the article, said last named means comprising means for gripping the opposite corners of the forward end of the web, means to move such corner gripping means apart to subject the forward end of the web to tension in a direction transverse to the length of the web, means for gripping the central portion of such thus tensioned forward end of the web, means for applying a back tension to the web longitudinally thereof over substantially its entire width, means to grip the side edges of the web throughout the length of the article and to subject such zone of the web to tension transversely thereto, and means to advance the article holding means and the stretched web relatively toward each other to contact the

surface of the web with the surface of the article to be covered.

3. Apparatus for stretching a web of flexible, somewhat extensible, material preliminary to its attachment across the face of an article comprising means for holding said article to be covered, means for holding a roll of web material, means for feeding web material from the roll, means to moisten the thus fed forward portion of the web to condition it for stretching, means for positioning a portion of the forward end of the thus fed web material, of a width to cover the face of the article, substantially in a plane spaced from the said face of the article, said last named means comprising means for gripping the opposite corners of the forward end of the web, means to move such corner gripping means apart to subject the forward end of the web to tension in a direction transverse to the length of the web, means for gripping the central portion of such thus tensioned forward end of the web, means for applying a back tension to the web longitudinally thereof over substantially its entire width, means to grip the side edges of the web throughout the length of the article, means to move the side edge gripping means apart to subject the web to transverse tension throughout said zone, and means to advance the article holding means and the stretched web relatively toward each other to contact the surface of the web with the surface of the article to be covered.

4. Apparatus for stretching a web of flexible, somewhat extensible, material preliminary to its attachment across the face of an article comprising an upstanding open framework of generally rectangular horizontal section, said framework incorporating means for feeding a web of the aforesaid material across the top of the framework longitudinally thereof, the framework having a vertical opening therethrough of such size and shape as freely to accommodate vertical passage therethrough of the article, the framework having at the top thereof spaced parallel horizontal clamps for engaging the side edges of the web, the framework further having at its top front portion a clamp for engaging the central portion of the forward end of the web, and, at the sides of such last named clamp, laterally movable clamps for engaging the forward corners of the web, means simultaneously and selectively to move said corner engaging clamps toward or away from each other, whereby the forward end of the web may be subjected to tension in a direction transverse to the length of the web, means for supporting the article within the vertical opening in the framework of the apparatus, and means for selectively raising or lowering the article supporting means, whereby the article may be raised into contact with the underside of the stretched portion of the web to subject such portion to predetermined tensions in all directions therealong.

5. Apparatus for stretching a web of flexible, somewhat extensible, material such as silk cloth or the like preliminary to its attachment across the face of an open, box-like screen frame, comprising an upstanding open framework of generally rectangular horizontal section, said framework incorporating supporting means on the rear of the frame for supporting a roll of web material, means for feeding from said roll the forward end of the aforesaid material across the top of the framework longitudinally thereof, the framework having a vertical opening therethrough of such size and shape as freely to accommodate vertical passage therethrough of the screen

frame, the framework having at the top thereof spaced parallel horizontal clamps for engaging the side edges of the web, the framework further having at its top front portion a clamp for engaging the central portion of the forward edge of the web, and, at the side of such last named clamp, laterally movable clamps for engaging the forward corners of the web, means simultaneously and selectively to move said corner engaging clamps toward, or away from each other, whereby the forward end of the web may be subjected to tension in a direction transverse to the length of the web, means for moving the side edge engaging clamps apart, means for subjecting the web to back tension longitudinally thereof, means for supporting the screen frame within the vertical opening in the framework of the apparatus, and means for selectively raising or lowering the screen frame supporting means, whereby the screen frame may be raised into contact with the underside of the stretched portion of the web.

6. Apparatus for stretching a web of flexible, somewhat extensible, material such as silk cloth or the like preliminary to its attachment across the face of an open, box-like screen frame, comprising an upstanding open framework of generally rectangular horizontal section, said framework having at the rear thereof means for supporting a roll of such web material, means supported on the framework for feeding web material from such roll across the top of the framework longitudinally thereof, the framework having a vertical opening therethrough of such size and shape as freely to accommodate vertical passage therethrough of the screen frame, the framework having at its top longitudinally extending spaced parallel side clamps bordering the vertical opening in the framework on both sides thereof, means mounting such side clamps for movement on the framework toward and away from each other, means simultaneously selectively to adjust the side clamps toward or away from each other, the framework having at its top front portion an elongated clamp for engaging the central portion of the forward edge of the web, a web corner engaging clamp mounted on the framework at each upper forward corner thereof, means simultaneously and selectively to move said corner engaging clamps toward or away from each other, whereby the forward end of the web may be subjected to tension in a direction transverse to the length of the web, means for subjecting the web to back tension longitudinally thereof, means for supporting the screen frame within the vertical opening in the framework of the apparatus, and means for selectively raising or lowering the screen frame supporting means, whereby the screen frame may be raised into contact with the underside of the stretched portion of the web.

7. The method of stretching a web of flexible material as a preliminary to its attachment to an article so as to lie substantially in a plane thereon which comprises positioning substantially in a plane a portion of such web material which is at least of sufficient length and width to cover the desired surface of the article, applying tension substantially from corner to corner to a first end of such portion of the web in a direction transverse to the length thereof, clamping the central portion of the thus tensioned first end of the web, applying a tension to the web longitudinally thereof over substantially its entire width, gripping the side edges of the thus tensioned web over substantially the full length of the aforesaid portion, and relatively advancing the article and

thus gripped and tensioned portion of the web toward each other in a direction generally normal to said stretched portion of the web, whereby to place the article firmly in contact with the web over the area of the former to be covered by the web.

8. The method of attaching a web of flexible material such as silk or the like to a box-like frame so as to form a printing screen lying substantially in a plane thereon, which comprises the following steps in the order named: positioning substantially in a plane the forward portion of a continuous web of such material, such portion being at least of sufficient length and width to cover the desired surface of the frame, applying tension substantially from corner to corner to the forward end of such portion of the web in a direction transverse to the length thereof, clamping the central portion of the forward end of the web, applying a back tension to the web longitudinally thereof over substantially its entire width, gripping the side edges of the web over substantially the full length of the aforesaid portion, pulling the gripped side edges of said portion away from each other to subject such portion to transverse tension, relatively advancing the frame and thus gripped and tensioned portion of the web toward each other in a direction generally normal to said portion of the web, whereby to place the frame firmly in contact with the web over the area of the former to be covered by the web.

9. The method of attaching a web of strong, flexible, somewhat extensible material across an open face of a frame which comprises the following steps: positioning the frame to be covered in a predetermined position, positioning a web of such material so that at least a portion thereof of a length exceeding the length of the frame at its forward end lies substantially in a plane parallel to and spaced from the juxtaposed surfaces of the frame, thoroughly moistening the web so as to condition it for stretching, the web being of a width exceeding the width of the frame, applying a predetermined tension substantially from corner to corner to one end of the web in a direction transverse to the length thereof, gripping the central portion of the thus tensioned forward end of the web over substantially its entire length, applying a predetermined tension to the web longitudinally thereof over substantially its entire width, gripping the side edges of the web over substantially the full length of the portion thereof lying over the frame, pulling the gripped side edges of said portion away from each other to subject such portion to transverse tension, moving the frame in a direction normal to the stretched web to bring the surfaces of the frame into contact with the adjacent side of the stretched portion of the web, and fastening the web to the surfaces of the frame with which it is in contact.

10. The method of attaching a web of strong, flexible, somewhat extensible material across an open face of a frame which comprises the following steps in the order named: positioning the frame to be covered in a predetermined position, feeding the forward end of a continuous web of such material from a supply roll so that a portion thereof of a length exceeding the length of the frame at its forward end lies substantially in a plane parallel to and spaced from the juxtaposed surfaces of the frame, in a portion of the path of feeding of the web thoroughly moistening the web so as to condition it for stretching, the web being of a width exceeding the width of the frame, applying a predetermined tension substantially from corner to corner to the forward end of the web in a direction transverse to the length thereof, gripping the central portion of the forward end of the web over substantially its entire length, applying a predetermined back tension to the web longitudinally thereof over substantially its entire width, gripping the side edges of the web over substantially the full length of the portion thereof lying over the frame, moving the side edges of the web away from each other and laterally from the vertical longitudinal planes in which they lay before being gripped to subject such portion of the web to transverse tension, moving the frame in a direction normal to the stretched web to bring the surfaces of the frame into contact with the adjacent side of the stretched portion of the web, continuing the moving of the frame to subject the stretched portion of the web to an additional predetermined tension in all directions, and fastening the web to the upper surfaces of the frame.
